(57) **CLAIM**

The ornamental design for an overcap, as shown and described.

DESCRIPTION

In a preferred embodiment the nature of this product is as an overcap for an aerosol container for dispensing various materials.

FIG. 1 is a right, top, frontal perspective view of an overcap embodying our new design;

FIG. 2 is a front elevational view thereof, the rear elevational view thereof being a mirror image thereof;

FIG. 3 is a right side elevational view thereof, the left side elevational view thereof being the mirror image thereof;

FIG. 4 is a top plan view thereof; and,

FIG. 5 is a bottom plan view thereof.

The broken line representation of internal cap structure in FIG. 5 is for purposes of illustration only and forms no part of the claim.
